UNITED STATES PATENT OFFICE.

BURT S. HARRISON, OF BROOKLYN, NEW YORK, ASSIGNOR TO DRYING SYSTEMS, INC.,
OF CHICAGO, ILLINOIS, A CORPORATION OF ILLINOIS.

AIR HEATER.

Application filed December 28, 1920. Serial No. 433,640.

To all whom it may concern:

Be it known that I, BURT S. HARRISON, a citizen of the United States, and resident of borough of Brooklyn, in the county of Kings and State of New York, have invented certain new and useful Improvements in Air Heaters, of which the following is a specification.

This invention relates to improvements in air heating furnaces designed particularly for the combustion of gaseous or liquid fuels.

The main object of the invention is to provide a heater which gives the maximum efficiency of heat transfer from the hot gases to the air to be heated, and at the same time overcomes all radiation losses from the combustion chamber by absorbing the radiated heat in the air to be heated.

I accomplish this object by the device illustrated in the accompanying drawings in which—

Figure 1 is a vertical longitudinal section of the device.

Figure 2 is a cross section of the same on the line 2—2 in Figure 1 and

Figure 3 is a cross section on the line 3—3 in Figure 1.

Fig. 4 is a side view of the air heater with the casing and the partitions 4 adjacent the outer wall of the casing shown in section.

The construction here illustrated comprises a horizontally disposed combustion chamber having a burner opening axially located at one end, so that the throw of the flame from the oil burner will be lengthwise of the chamber. The area of the combustion chamber is sufficient for the complete combustion of the gases before they leave the combustion chamber. The spent gases in the combustion chamber leave from the end of the horizontal cylinder and then pass in series through a plurality of groups of tubes extending lengthwise of and arranged in a concentric circle around the combustion chamber. The air to be heated enters a surrounding casing and travels in a transverse manner with reference to the tubes and counter-current with reference to the flow of the gases of combustion, that is, the incoming air strikes the tubes first which carry the gases of the lowest temperature or those nearest the stack, and then progressively strikes the hotter tubes and finally passes transversely over the shell of the com-

bustion chamber and leaves the heater at that point at the highest temperature.

Similar characters of reference refer to similar parts throughout the several views.

My improved device is provided with an internally fired horizontal combustion chamber 1 which is lined with fire brick or other refractory material 2 contained within a casing 3. Intermediate the combustion chamber 1 and the casing or shell 3 I provide a plurality of annular spaced partitions 4. Extending through these partitions from end to end of the device, I provide a plurality of tubes 5, 5¹ and 5² which are preferably expanded at their ends into the front and rear partitions.

At the rear of the device, I provide an annular smoke box 6 which embraces the outlets of the upper tubes 5, and at the front of the device I provide an annular smoke box 7 which embraces the ends of all of the tubes. At the upper part of the smoke box 7 I provide a smoke-uptake 8.

The gases of combustion pass from the combustion chamber 1 into the lower tubes 5¹ at the rear of the device and are thence drawn through these tubes to the smoke box 7 at the front of the heater and pass thence through the side tubes 5² to the rear smoke box 6, and thence are returned through the upper tubes 5 to the smoke box 7 and are thence discharged through the smoke uptake 8.

Baffle plates 9 and 10 are provided in the smoke boxes 6 and 7 respectively to direct the gases of combustion through the several series of tubes as above described. As shown in Fig. 1, the combustion chamber 1 communicates at the rear of the furnace with a set of tubes 5¹. The products of combustion are conducted by the tubes 5¹ in the direction indicated by the arrows in Fig. 4 to the smoke box 7, from which the products of combustion are conducted by the tubes 5² to the smoke box 6, but above the baffles 10, separating the inlets of tubes 5¹ from the outlets of tubes 5². From the smoke box 6 the products of combustion then travel again to the front of the furnace through the tubes 5 into smoke box 7 above the baffles 9 which divide the smoke box 7 into two compartments, the lower compartment providing communication between the outlets of tubes 5¹ and the inlets of tubes 5². The baffles 9 prevent direct

communication between the lower compartment and the upper compartment, into which tubes 5 discharge. I preferably support the device on a suitable seat 10^a of saddle 11.

Fresh air from a suitable source of supply is preferably supplied through the port 13 under pressure by means of a fan or other similar device, not shown, to the chamber 12 between the combustion chamber 1 and the shell or casing 3 which is preferably divided by an annular partition 15, and passes thence around this chamber in contact with the tubes 5¹ and 5² containing the heated gases of combustion and thence passes around the end 15¹ of the partition 15 and is conducted back between the partition 15 and the combustion chamber 1 in contact with the combustion chamber 1 and passes out by the discharge pipe 14 from which it is supplied to the rooms or chambers to be heated. As will be apparent, the fresh air at the point of introduction to the device and, therefore, at its point of lowest temperature, is brought into contact with the upper tubes containing the gases of combustion most remote from the source of heat and therefore at their lowest temperature. This fresh air meets, in its passage, tubes containing the gases of combustion of progressively higher temperature so that the maximum heating efficiency of the gases of combustion is attained and the temperature of the heated air may be brought to the temperature of the gases of combustion.

When desired, and where moderate temperature is required, the annular partition 15 may be omitted and the air circulated about the combustion chamber.

Having thus described my invention what I claim is:

1. In a device of the character described, the combination of a horizontal combustion chamber, a plurality of horizontal ducts for the gases of combustion positioned around the combustion chamber, a plurality of baffle plates separating the said ducts into sections and adapted to direct the gases of combustion through successive sections of said ducts, a fresh air duct, a heating chamber

and an annular dividing plate in said heating chamber whereby the fresh air is brought into contact with heating surfaces of progressively higher temperature.

2. In a device of the character described, the combination of a horizontal combustion chamber a heating chamber surrounding the combustion chamber, a duct for the heated gases of combustion, baffle plates arranged to divide the said duct and means for conducting fresh air around said heating chamber in contact with sections of progressively increasing temperature.

3. In an air heater of the class described, the combination of a horizontal combustion chamber, a plurality of horizontal smoke tubes arranged concentrically around the combustion chamber, a shell surrounding said tubes and combustion chamber, transverse partitions in said shell, and means for conducting fresh air through the spaces in said shell formed by said partitions.

4. In an air heater of the class described, the combination of a horizontal combustion chamber, a plurality of horizontal smoke tubes arranged concentrically around the combustion chamber, a shell surrounding said tubes and combustion chamber, transverse partitions in said shell, means for conducting fresh air through the spaces in said shell formed by said partitions, an annular partition between said tubes and the wall of the combustion chamber, and means for effecting a flow of air progressively past the tubes between said annular partition and shell and then between said annular partition and the combustion chamber.

5. In an air heater of the class described, a horizontal combustion chamber, a surrounding shell providing an air space entirely surrounding said combustion chamber in a transverse plane, a plurality of groups of smoke tubes located in said air chamber and parallel with and surrounding the combustion chamber, means for directing the products of combustion from the combustion chamber successively through said groups of tubes, and means for directing the air through said air chamber.

BURT S. HARRISON.
